SELF-REINFORCING FABRIC.

1,300,515.

Specification of Letters Patent. Patented Apr. 15, 1919.

Application filed October 27, 1917. Serial No. 198,768.

To all whom it may concern:

Be it known that I, CHARLES B. TEWKSBURY, a citizen of the United States, residing at West Roxbury, in the county of Suffolk and State of Massachusetts, have invented 5 certain new and useful Improvements in Self-Reinforcing Fabric, of which the following is a specification.

This invention relates broadly to a self-reinforcing plastic fabric or construction 10 adapted for use in bags, tickets, tags and the like, and more especially to such parts of said articles as are provided with fastening or attaching devices of, for example, string 15 or wire.

Articles which embody the present invention possess the novel property that when they are placed under a stress which tends to disrupt them, they act automatically to reinforce themselves against such disruptive 20 stress and counteract or distribute it; this being one of the principal objects of the invention.

Another object of the invention is to obviate the tendency for the string or the like,—when, in one form of the device a string is employed, looped noose-fashion around a part of the sheet material near one edge of the latter,—to crush or break 30 this edge when said string is placed under tension.

Still another object of the invention is to provide an edge-reinforced article, in which the presence of the preferably extended reinforcing element or elements thereof does not prevent the presentation of a flat printing or writing surface upon one side of the article, while the attaching cord or wire is prevented, in the preferred forms of the device, 35 from forming too sharp a bight in said cord at the point where the latter is most likely to break, when said cord is placed under stress.

These and other objects of my invention 40 will be hereinafter referred to and the novel and, it is believed, ingenious, although preferably exceedingly simple combinations of means and elements whereby said objects are attained, will be more particularly set forth in the claims appended hereto.

In the drawing which forms a part hereof,

I have exemplified preferred forms of my novel construction; but as I am aware of many applications of the invention and of various changes and modifications which 55 may be made in the embodiments thereof given by way of exemplification, I desire to be limited only by the scope of said claims.

Referring to the drawing:

Figure 1 is a back view of a tag which exemplifies one form of my invention.

Fig. 2 is a vertical section of said tag; the section being taken on the line II—II of Fig. 1.

Fig. 3 is a similar section, showing the disposition of parts when the attaching cord is placed under disruptive stress.

Fig. 4 is a back view of the upper part of the tag corresponding to Fig. 3, in so far as 70 the disposition of parts is concerned.

Fig. 5 is a view corresponding to Fig. 1 but of a modified construction.

Fig. 6 is a view similar to Fig. 5, of a still further form of the device.

Fig. 7 is a section taken on line VII—VII of Fig. 6.

Fig. 8 is a view of the tag shown in Fig. 6 after parts thereof have been deformed by the imposition of stress.

Fig. 9 is a section taken on line IX—IX of Fig. 8; and

Fig. 10 is a perspective view of a fragment of a bag or the like, showing the application of one form of the improved 85 construction thereto.

In Fig. 1, the tag body preferably consists of an oblong piece of tough card paper or other suitable sheet material 1, to which is affixed, by means of any suitable adhesive, 90 a more or less extended sheet or strip 2; these parts being so assembled as to retain in place between them a strand or the like of reinforcing material 3. This may conveniently be string and preferably extends parallel and relatively close to the upper edge of the tag, from side to side of the latter.

As best shown in Fig. 2, this reinforcement is preferably received entirely into the 100 retaining strip 2; the latter having therein a groove of substantially the same depth as

the thickness of the reinforcing cord, to the end that the left-hand face of the sheet 1, as viewed in Fig. 2, may be substantially flat over its entire surface. This feature 5 self-evidently affords the best writing or printing surface; there being no ridge upon the sheets such as would interfere with the impression of characters from type or with the pen, when printing or writing is being 10 placed upon the article.

The attaching cord or wire 4 of the tag or other article, may be looped through an opening or hole 5 in the latter; and this cord may take the form of what is, in effect, a 15 slip noose. It will be observed that the aperture 5 is disposed at some distance from the reinforcement 3; and at first sight it might be thought that this unusual disposition of said opening was disadvantageous in that 20 the tag material upon the side of this hole against which the cord bears, is unreinforced, and hence is much more likely to tear as the result of a comparatively slight pull upon the tag. This might be the case 25 were this aperture very close to, or substantially in contact with the reinforcing cord 3. By reason, however, of this disposition of said opening, with respect to the reinforcement, a novel result is attained. As 30 indicated by the arrow adjacent the left-hand side of the cord 4 in Fig. 2, when this cord is pulled with respect to the tag, said cord tends to move in the direction of this arrow, and after sufficient tensile stress has 35 been imposed, the paper or other substance of which the body of the tag is formed, commences to tear substantially on the lines 6—6, indicated by dots and dashes in Fig. 1. These lines, it will be observed, diverge 40 and at the same time that this tearing occurs, the action of the cord is such that it usually tends to roll up, in a measure, the torn material, so that finally a more or less perfectly shaped roll 7 is formed, as shown 45 in Fig. 3.

This roll continues to form until such deformation of the sheet material is arrested by the reinforcement 3, at which time the substantially rectilineal line of contact between the abutment, provided by the reinforcement, and the so formed roll or pad is quite extended; since by the time that the diverging tearing lines 6 reach their limits, the distance therebetween is very much 55 greater than even double the thickness of the attaching cord.

In other words, were it not for this novel provision and had the aperture 5 been placed in juxtaposition to the strand 3, the disruptive stress would at once have been exerted 60 against this reinforcement and said stress would have been applied along a line no longer, at most, than double the thickness

of the cord. This stress would then be exerted through this very short length of this 65 reinforcement, against the layer of adhesive immediately thereto and would tend to tear the reinforcement out of its recess or recesses, the strand 3 being bowed; and as this bowing continued, the rupture of the 70 layers 1 and 2 beyond the reinforcement having thus once been started, there would be a marked tendency for further yielding to occur until finally the reinforcing strand 3 would be pulled completely out, and the attaching member 4 would then be separated 75 from the tag body. If said tag had been attached to a trunk, for example, then the owner in such case would be very apt to encounter considerable difficulty in re-locating 80 his wardrobe; a difficulty which many have from time to time experienced.

Now, on the other hand, however, when an article is constructed in accordance with the present invention so as to, in effect, produce 85 a self-reinforcing device, this trouble is substantially eliminated; because no longer is the thrust of the bight or loop in the attaching cord exerted against what is practically a single point, but rather is it exerted 90 against a line which is at least as long as the distance between the upper ends of the dash and dotted lines 6; and furthermore this stress is exerted through a pad which cushions and distributes it quite uniformly 95 along said line. Obviously, in such case, a very much greater extent of adhesive must give way before there can be any start whatsoever of the reinforcing cord 3 out from between its retaining layers. 100

As a matter of fact, in practice, it has been found that the tag is thereby very greatly strengthened, and this, without having to appreciably increase the cost of the article.

It should also be noted that at the point 105 where the attaching cord is most apt to break,—namely, where it curves around sharply through about 180° after having passed downwardly on the right-hand side of Fig. 2,—the so formed bend in the cord 110 has the radius thereof quite materially lengthened when said cord is compelled to pass around the relatively large roll 7; so that here also the cord itself is, in effect, strengthened. 115

I have observed, too, that whereas when I had placed the hole 5 in juxtaposition to the reinforcing strand 3 and formed an attaching cord in the form of a noose, as in the cord in question, there is a strong tendency for the bight 8 in the cord, or the parts immediately adjacent thereto, to tear or crush the upper edge of the tag; but that when the tag is formed in the manner shown, so as to permit of the formation of 120 the roll 7, this tendency practically disap-

pears. I can only account for this upon the theory that as the cord is placed under sufficient tension to cause the sheets to tear on the lines 6-6, there is quite a free movement 5 of the cord on the left-hand side thereof adjacent to and in the direction of the arrow shown in Fig. 2, and this free play of the cord enables its bight 8 to pass toward the right as viewed in Fig. 3, while settling 10 closer to the upper edge of the tag, until it reaches a point where, when the roll 7 has been fully formed, the line of application of the stress has been so shifted toward the right-hand surface of the tag, as viewed in 15 Fig. 3, that any tendency for the parts of the cord immediately on either side of the bight 8 to nip down into said edge, is counteracted by the upward pull.

Whether this theory is correct or not, I 20 can not positively say, but in any case the effect is to tend to preserve the edge.

It is of course possible to cause the progressively laterally extending deformation, which in this case is the roll 7,—to have a 25 still wider base, after it has been formed, by so slitting or notching the wall of the aperture 5', as shown in Fig. 5, as to cause the lines of tear 6' to commence at a greater distance apart. As, however, articles formed 30 in accordance with the construction shown in Fig. 1 have been found in practice to be amply strong, and since further the cost of a punch for making such an aperture as that designated 5' is obviously greater than 35 that for the hole 5, the construction shown in Fig. 1 is to be preferred.

I have also discovered that it is possible 40 to obtain a very similar, although not precisely the same, action, when the attaching member, in this case designated 4', is simply looped singly through the opening 5, as shown in Figs. 6 and 7.

Herein, the cord may conveniently be 45 knotted as at 9, to prevent its separation from the tag. In this case, when said cord is placed under operative stress, as in Figs. 8 and 9, the result is to crumple up the sheet material in its path, as indicated at 10, to again form a stress distributing cushion or 50 pad; although one somewhat dissimilar to that above described. If the reinforcing cord 3' be partly embedded in the sheet 1 and partly in the sheet 2, this crumpling will take place about equally on each side 55 of the tag, as shown in Fig. 9; and what seems to occur is that the sheet material tears on the lines 6'' which diverge from each other at substantially 90° (the angle of divergence being even greater than that 60 shown in Fig. 1); and while in some places the adhesive layer between the two sheets, where two sheets are employed, may at times give way, to permit each of the sheets to

independently crumple in spots,—in others the two sheets will crumple together. In 65 any case the strain is distributed along a considerable extent of the abutment provided by the reinforcement; with the result that the so formed connection is very resistant to rupture.

When the reinforcement 3 or 3' is extended adjacent an edge of the article for 70 any material distance, as shown, it not only performs its function of providing an abutment as above described; but it further strengthens such edge against rupture downwardly therefrom into the sheet for any considerable distance, wherever said edge is 75 thus reinforced.

While the preferred constructions are 80 peculiarly applicable to or capable of embodiment in tags or the like, the invention in its broader aspects is by no means limited to such articles, but may be used in connection with various articles of manufacture, such for example as bags and other devices formed of sheet material.

In Fig. 10 I have therefore shown an upper corner of a bag 11, provided with cords 4, similar to those shown in Figs. 1 and 2, for attaching or fastening the respective sides of the mouth thereof together, or for 85 supporting the bag.

Herein the sheet material of the bag may 90 be, if desired, quite thin but sufficiently strong for the purpose for which the article is intended, while in such case, the edging or strip 2 is of sufficient thickness and stiffness, that when the relatively small portions thereof (between the tearing lines 6) are deformed and rolled or bent over upon themselves to form a plurality of superposed layers, said portions will, in effect and technically speaking, constitute a short beam; 95 since either of the above described pads or 100 masses 7 or 10 may be so considered.

The connecting or attaching member or device 4 is attached to the sheet material as 110 shown, to effect the desired deformation in the latter when said member is subjected to operative stress; and the strand 3, embedded in the strip 2 coacts with the area A of the sheet material which lies transversely across the line of initial stress, between the lines B-B, to establish an abutment forming 115 means to limit the extent of said deformation and support said beam upon one side thereof throughout substantially its length; the unevenly distributed load,—which is really imposed upon the opposite or lower side of the deformation at but a point or two therein, practically midway of its length,—being then quite uniformly distributed to said abutment forming means 120 through the thus superposed layers of the 125 sheet material.

Having thus described my invention, what I claim is:

1. A self-reinforcing article comprising in combination, an attaching member, sheet material having an aperture for the reception of said attaching member, and an extended reinforcement for said material embedded therein in the path which that part of the attaching member which is disposed 10 in said aperture tends to follow when the attaching member is under operative tension, said part being spaced from said reinforcement at such time by a stress distributing pad formed from parts of said sheet material.
2. A self-reinforcing article comprising in combination, an attaching member, sheet material having an aperture for the reception of said attaching member, an extended 20 reinforcement for said material adhesively embedded therein in the path which that part of the attaching member which is disposed in said aperture tends to follow when the attaching member is under operative tension, said article having provisions to automatically form in a portion thereof, lying 25 in said path, a stress distributing pad between said part of said member and said reinforcement when said member is placed under said tension.
3. A self-reinforcing article comprising in combination, an attaching member, sheet material having an aperture for the reception of said attaching member, an extended 35 reinforcement for said material embedded therein in the path which that part of the attaching member which is disposed in said aperture tends to follow when the attaching member is under operative tension, said article having provisions to automatically form in a portion thereof, lying in said path, a cushion between said part of said member and said reinforcement, when said member is placed under said tension.
4. A self-reinforcing article comprising in combination, an attaching member, sheet material having means for receiving and engaging a part of said member, a reinforcement for said material, and provisions to 40 co-act with said reinforcement and member to automatically strengthen the article against disruptive separation of its attaching member therefrom when and as deformation of a part of said sheet material by 50 said member is effected.
5. A self-reinforcing article comprising in combination, an attaching member, sheet material connected thereto for initial and progressively laterally extended deformation in parts thereof by said member when 55 said connection is subjected to operative stress, said deformation being extended laterally with respect to the line of said stress,

and means for arresting said deformation to enable it to distribute said stress through an area in said material extending transversely to said line of stress. 65

6. A self-reinforcing article comprising in combination, an attaching member, a multiply body of sheet material connected thereto for initial and progressively laterally extended deformation of parts of the plies of said body when said connection is subjected to operative stress, said deformation being extended laterally with respect to the line of 70 said stress, and means, disposed between the plies of said body, for arresting said deformation to enable it to distribute said stress through an area of said body extending laterally to said line of stress. 75

8. A self-reinforcing article comprising in combination, an attaching member, sheet material connected thereto for initial and progressively extended deformation of a part of said material when said connection 85 is subjected to operative stress, and means to definitely arrest said deformation and provide a relatively extended abutment therefor presenting a substantially rectilinear face to the arrested deformation, said face 90 extending substantially at right angles to the line of said stress and the rectilinear length thereof being substantially equal to the width of said deformation. 95

9. An article of the class described which comprises sheet material of such thickness and stiffness that when relatively small portions thereof are deformed and bent over upon themselves to form a plurality of superposed layers, said portions will, in effect, constitute a short beam, a connecting device attached to said sheet material to effect said deformation when subjected to operative stress to separate it from said material, and abutment forming means to limit the extent 105 of said deformation and support said beam upon one side thereof throughout substantially its length, the unevenly distributed load imposed upon said beam on its opposite side by said stress being then substantially uniformly distributed to said abutment forming means through said superposed layers. 110

10. A self-reinforcing article comprising in combination, sheet material having means 115 for receiving and engaging an attaching member, a reinforcement for said material, and provisions to co-act with said reinforcement to automatically strengthen the article against disruptive separation of its attaching member therefrom when and as deformation of a part of said sheet material by 120 the imposition of disruptive stress thereupon, is effected.

11. A self-reinforcing article comprising in combination, an attaching member, sheet

material having an aperture for the reception of said attaching member, and deformation arresting means attached to said sheet material in the path which that part of the attaching member which is disposed in said aperture tends to follow when the attaching member is under operative tension, said part being spaced from said reinforcement at such time by a stress distributing pad formed from parts of said sheet material.

In testimony whereof I have affixed my signature, in the presence of two witnesses.
